UNITED STATES PATENT OFFICE.

CHARLES J. KINTNER, OF NEW YORK, N. Y.

MEANS FOR ATTACHING FLEXIBLE TUBES TO SOURCES OF WATER-SUPPLY.

No. 863,571.

Specification of Letters Patent.

Patented Aug. 13, 1907.

Application filed January 14, 1907. Serial No. 352,398.

To all whom it may concern:

Be it known that I, CHARLES J. KINTNER, a citizen of the United States, residing in the borough of Manhattan and city, county, and State of New York, have made a new and useful Invention in Means for Attaching Flexible Tubes to Sources of Water-Supply, of which the following is a specification.

My invention is directed particularly to novel means for connecting flexible water tubes, such as are used 10 with the roses of portable shower-baths directly to faucets of water systems, in such manner as to prevent the same from being blown off when under relatively high pressure, and it has for its objects—first, the provision of means of this nature which is adapted to fit 15 the mouth or nozzle of any of the well known types of faucets now in general public use and of varying size or conformation, and in such manner as to, when secured thereto, prevent any possibility of back-flow or blowing off of the attached part, due to the pressures 20 ordinarily prevailing in water supply systems. Second, to provide means of this nature which is simple and cheap of construction, quickly and easily applied, and readily adapted for use with the faucets of wash-basins, bath-tubs, sinks, or in fact at any point about 25 a house where the user may choose to apply the improvement.

For a full and clear understanding of my invention, such as will enable others skilled in the art to construct and use the same, reference is had to the accompanying 30 drawings, in which are shown my novel appliances for connecting such devices to the mouths of faucets of variable diameters and conformations, such as are ordinarily found in connection with bath-tubs or stationary wash-basins, sinks, etc.

35 Figure 1 is a vertical sectional view of one form of such connector, illustrating the means of tying or lashing the same to a faucet. Fig. 2 is a perspective view of the same in which the lashing means is interlaced through a series of holes or openings beneath a bead or 40 rim at the mouth of the connector; and, Fig. 3 is a similar view in which the lower end of the connector is cylindrical and of larger diameter than the smaller cone-shaped end of the connector proper. Fig. 4 is a perspective view of the conformation shown in Figs. 1 and 2 illustrating the lashing or fastening means as being in the nature of a chain, connecting rings and a hook. Fig. 5 is a side elevational view of a water-cock 45 of relatively small diameter and peculiar conformation, illustrating also the manner of applying my novel form 50 of flexible connector thereto.

Prior to my invention attempts had been made to connect shower-bath roses or analogous devices for use with flexible tubes directly to the faucets of stationary sources of water supply, such devices usually being in 55 the nature of rubber bulbs adapted to be slipped over the mouth of the faucet and held there frictionally, a

number of such devices being well known and in general public use. With all such devices, however, so far as I am aware, it was found that where the pressure was excessive, as in many water systems for the supply 60 of cities, they would be blown off, thus defeating the object for which they were devised. Nor has it heretofore been possible to devise a flexible connector of the character indicated which will adapt it for use with faucets of variable diameters or variable cross section; 65 most faucets in public use being cylindrical in cross section; while others, such as are utilized with stationary wash-basins are often elliptical in cross section, so that it has been found impossible to devise a flexible connector of the nature indicated which will 70 fit or adapt itself to the various conditions of usage thus indicated. Connectors of this general nature had also been devised in which the end of the rubber tube itself was expansibly forced over the mouth of a faucet and held in connection therewith by clamping rings 75 and a chain; such devices, however, having a limited use in that they were not adapted to fit on or over widely divergent types of faucets found in the general market, many of which vary not only in diameter but in relative cross section, so that connectors of this latter type were not practical for such use. Connectors 80 for such uses had also been devised in which a cone-shaped flexible part was secured within a rigid metallic cup part and provided with means for fixedly securing all the parts directly to a faucet, in one instance by a 85 chain and in another by thumb-screws; while a further connector of this nature had been devised for securing hose to a water-cock or faucet, in which the end of the hose was slipped over the mouth of the faucet and a flexible or yielding rubber neck located within 90 the mouth of the hose was inserted within the mouth of the faucet, the parts all being held securely thereto by a metallic locking collar and chain, and I make no claim hereinafter broad enough to include any of the 95 before-mentioned structures, the most generic features of my invention being the provision of a flexible cone-shaped part provided with means secured directly to the base or mouth thereof for lashing or tying the same securely about the mouth of the faucet in such manner that when the flexible connector expands 100 there is no possibility of its being blown off; or no possibility of back-flow of water, my novel connector being of such a nature that by reason of its flexibility it is permitted to expand under relatively high pressures, thereby permitting a flow of a volume of water of greater or less amount, dependent upon the pressure.

105 My invention consists in devising a cone-shaped connector, the lower or smaller internal diameter of which is relatively smaller than the exterior diameter of the smallest faucet in the market, whether cylindrical or elliptical in cross section, and the internal

diameter of the base or mouth of such cone-shaped connector is of relatively greater diameter than that of the largest faucet in the market.

I have ascertained that, as a rule, faucets of the 5 smallest diameters existing in the market are about one-half an inch in exterior diameter; whereas faucets of the largest diameters, such as are utilized in bathtubs and often provided with screw-connections, are about $1\frac{1}{4}$ inches in exterior diameter. Faucets of 10 elliptical cross section are also found in the market in which the axes of the ellipses vary from $\frac{1}{2}$ to one inch and even more. I, therefore, construct a cone-shaped flexible connector, preferably of the best soft rubber and preferably provided with a bead or rim at 15 its base or mouth beneath which I provide holes or openings in which is secured in any preferred manner flexible means, preferably in the nature of a braided cord—water proofed or not as desired—for lashing the connector either fast to the mouth of the faucet itself 20 or to some part of the fixture in such manner as will readily suggest itself to the user.

My invention will be fully understood by referring now to the drawings in detail, in which 1 represents the cone-shaped connector having a cylindrical extension 25 from its smaller end for attaching it to the flexible hose or pipe to be used, through the agency of any well known form of tubular connector.

2 represents a bead or rim at the base or mouth end, and 3, 3, represent two cords made preferably of 30 braided material, and provided in this instance with a knot at each end, the inner knots being located in the manner shown.

In Fig. 2 of the drawings I have illustrated a single 35 cord 3 which is looped or woven through any number of holes or openings—preferably four—located directly beneath the bead or rim 2 in the manner shown and adapted to act in the manner of a draw-string.

In Fig. 3 I have illustrated the connector as having 40 an enlarged cylindrical extension 4 provided with a second rim or bead 2 at its lower end, the function of which parts is to enable the use of a connector of larger diameter than would be utilized in connection with connectors having the smallest diameter to enable the attachment of the same to nozzles of very small exterior diameter. In this form of the invention the cord 45 3 is looped through two diametrically opposite holes located directly below the bead or rim 2, as clearly shown.

In Fig. 4 I have shown still another means for lashing 50 or tying the connector to a faucet or stationary fixture, the same consisting of a chain with rings and a hook, the use of which will be obvious on inspection of the drawings. In using this connector it is first drawn snugly over the mouth of the faucet 5, after which the 55 cord or cords 3 may be utilized in any preferred manner for effecting the attachment of the connector in such way as to prevent its being blown off or prevent any back-flow. To make a single illustration, where a fixture is provided with a stem and a cock the loop 60 of the cord might be drawn outward and carried over the cock and the stem, after which the two free ends might be drawn in such manner as to put the loop under strain against the bead or rim 2, after which said free ends could be lashed several times around the body 65 of the connector as firmly and securely as possible;

finally tying a single flat knot, the cord being sufficiently stiff to afford the desired amount of friction and thus prevent any possibility of the connector being blown off or of any back-flow. With the form shown in Fig. 4 the chain would preferably be carried around 70 the stem of the faucet or cock and the connector drawn firmly over the mouth of said cock, after which the hook would be secured to the desired one of the links, thus holding the parts securely together.

It will be clearly apparent, therefore, that with the 75 preferred form of connector and the flexible cord attachment as illustrated in Figs. 1, 2, 3 & 5 such a flexible or yielding cone-shaped means of attachment adapts itself to all sizes and forms of faucets and that after the same is secured to the faucet in the manner just indicated, any expansion of the connector due to excessive pressure will not permit of any back-flow; nor will it be possible to blow it off owing to the tensile strain of the cord about the same. In Fig. 5 I have shown the application of my novel connector to a faucet having 80 a relatively small diameter and a very short stem. In this instance the base or mouth of the flexible connector 1 is turned backward upon itself so as to enable the lower or smaller portion of the coned part thereof to be drawn snugly over the mouth of the faucet, after 85 which the cords 3, 3, may be wound tightly around the body part thereof or secured to the faucet in any preferred manner, this figure of the drawings illustrating the extreme flexibility of my novel connector as adapting it to faucets of peculiar conformation. It is also 90 apparent that by reason of the adjustability of the cord, as shown in Figs. 2, 3 and 5, it may be drawn in either direction so as to increase the length thereof for the purpose of attaching the connector to some part of a fixture which may be more or less distantly removed. 95 I prefer to make this cord 3 of about one yard in length so that when it is adjusted in the manner shown in Figs. 2 and 3 there will be about 17 inches of free cord at each end which may be utilized for tying or lashing the connector in many ways, and which cord when 100 drawn through, so that one of the knots rests against the face of the connector, will have an exposed length of approximately 34 inches which adapts it for connection in a number of ways and in such manner, as before stated, as will positively prevent its being blown off 105 or the escape of any water in the nature of back-flow.

I do not limit my invention to the especial details of construction illustrated in the accompanying drawings, as a number of the features thereof might be materially departed from and still come within the scope 115 of my claims hereinafter made. I believe it is broadly new with me to provide a cone-shaped flexible or yielding connector for attaching tubes or pipes to stationary sources of water supply provided with cocks having variable diameters or variable cross sections, and to secure the same thereto, so that it cannot be blown off, by means adapted to lash or tie the same either directly to the faucet itself or to some stationary 120 part of the fixture and in such manner as to absolutely prevent back-flow of water, and my claims are generic 125 as to these features. Nor do I limit the use of my novel connector with shower-bath roses, as obviously it may have numerous analogous uses, as, for instance, with syringes like that described in a prior patent granted to me on the 17th day of July, 1906, and num- 130

bered 826,172 and with which the form shown in Fig. 3 has an especial adaptability, the extension 4 and the lower bead 2 at the end thereof permitting the use of a venting connector grooved exteriorly for venting the water when the cut-off of the syringe is closed, or the flow through the nozzle checked in the manner disclosed in said patent.

Having thus described my invention what I claim and desire to secure by Letters Patent of the United States is—

1. A flexible tube provided with a cone-shaped connector and flexible means in the nature of a cord for securing said connector to the faucet of a source of water supply, substantially as described.
2. A flexible cone-shaped connector having a cylindrical extension at its smaller end and flexible means secured to its larger end for tying it to a faucet, substantially as described.
3. A flexible cone-shaped connector having a cylindrical extension at one end and a bead at the other with holes located beneath the bead, and a cord secured therein, substantially as described.
4. A flexible cone-shaped connector having holes located at points near the base of the cone and a cord secured therein, substantially as described.
5. A flexible cone-shaped connector having a cord secured to the base thereof for tying it to a faucet, substantially as described.
6. A cone-shaped connector adapted to fit over the mouths of faucets of different diameters or variable conformations, and flexible means attached to said connector and adapted to secure it so that it will not blow off, and

that back-flow of water will be prevented, substantially as described.

7. A cone-shaped connector having a cylindrical extension at one end and flexible means at the other adapted to secure it to some stationary point of support, substantially as described. 35

8. A cone-shaped connector of flexible material having a cylindrical extension at one end and a bead at the other; 40 in combination with a cord secured beneath the bead for tying said connector to a stationary point of support, substantially as described.

9. A cone-shaped connector of flexible material having a cylindrical extension at its smaller end of larger diameter than the latter; in combination with means for securing said connector about the mouth of a faucet, substantially as described. 45

10. A cone-shaped connector of flexible material having a cylindrical extension at its smaller end of larger diameter than the latter; in combination with means for securing said connector about the mouth of a faucet, each end of the connector being provided with a bead, substantially as described. 50

11. A cone-shaped connector of flexible material having a cylindrical extension at its smaller end of larger diameter than the latter and provided at each end with a bead; in combination with a cord for securing the connector directly to some point of attachment adjacent thereto, substantially as described. 55

In testimony whereof I have signed my name to this specification in the presence of two subscribing witnesses.

CHARLES J. KINTNER.
